COLLAPSIBLE CARRY HOME CONTAINER

William J. Wells, Buffalo, N. Y., assignor to F. N. Burt Company, Inc., Buffalo, N. Y., a corporation of Delaware

Application April 4, 1939, Serial No. 265,962

1 Claim. (Cl. 224—45)

This invention relates to improvements in article containers, and more particularly to that type of container ordinarily utilized for carrying bottles or similar articles for short distances, such as delivering them to the consumer from the retailer.

It is a general object of the invention to provide a collapsible carry home container or article carrier of the class mentioned, constructed and arranged in an improved manner so that it may be readily collapsed into a small article or package for quantity shipment, and moreover, is capable of being set up into condition for use by a very simple operation that may be very quickly effected by the user.

A further and more particular object of the invention is to provide an improved carry home container or article carrier of the class mentioned, constructed of a single sheet of material such as cardboard, fiberboard, and the like, appropriately fabricated and connected into a continuous or endless band or sheet so that it can be collapsed into a small space for shipment and also expanded or set up into condition for supporting and carrying the bottles or other articles by a very simple movement that can be quickly and easily accomplished.

Still another object of the invention is to provide an improved carry home container of the class mentioned utilizing a structural sheet member provided with hinge elements such as creases upon which the sheet may be bent or folded into collapsed condition, or expanded by a very simple movement into a set up condition for receiving and carrying the articles.

Other objects of the invention will be in part pointed out in the following detailed description of certain illustrative but preferred embodiments of the invention, and will be in part obvious in connection therewith.

The invention accordingly comprises the features of construction, combination of elements, and arrangement of parts, which will be exemplified in the construction hereinafter set forth and the scope of the application of which will be indicated in the claim.

For a more complete and comprehensive disclosure of the invention reference is had to the following detailed description of the illustrative embodiments, and to the accompanying drawings in which:

Fig. 1 is a perspective view of a carry container especially adapted for carrying bottles or similar articles, and constructed and arranged in accordance with the invention;

Fig. 2 is an end elevation thereof, parts being in section;

Fig. 3 is a fragmentary enlarged vertical transverse sectional view showing the handle structure at the upper extremity of the carrier;

Fig. 4 is a detailed fragmentary perspective view of the bottom of the carrier of Figs. 1 and 2;

Fig. 5 is an end view of the container of Figs. 1 and 2 in partially collapsed condition;

Fig. 6 is an end view similar to Fig. 5 but showing the container fully collapsed;

Fig. 7 is a plan view of the sheet or blank fabricated to form the container;

Fig. 8 is an end elevation similar to that of Fig. 2 but showing a modified form of the invention;

Fig. 9 is a horizontal sectional plan of the lower part of the carrier of Fig. 8 showing the manner of splicing the adjacent ends of the blank together;

Fig. 10 is a detailed sectional view of the splice shown in Fig. 9;

Fig. 11 is an end view of the carrier of Fig. 8 in collapsed condition; and

Fig. 12 is a plan view of the blank or sheet member of Fig. 8 fabricated to form the carrier.

Referring to Figs. 1 to 7 inclusive of the drawings for a detailed description of the embodiment of the invention there shown, it will be noted that the carry container or article carrier embodies in its construction a single structural sheet member 15 which may be constructed of suitable fibrous sheet material such as cardboard, pasteboard, fiberboard, or the like. This structural sheet member is preferably formed of a single integral sheet fabricated or preformed so that it may be readily set up or assembled from the preformed sheet into the form of the complete carrier container.

As particularly shown in Fig. 7, the blank or structural sheet member 15 is preformed with transversely extending hinge elements 16, 17, 18, 19 and 20. These hinge elements in the embodiment herein disclosed extend substantially parallel to each other in longitudinally spaced relation transversely of the blank or sheet member 15. While these hinge elements may be formed in any preferred manner to permit bending of the blank thereon, it is preferable to form them in the manner indicated diagrammatically in the drawings by weakening the sheet to bending thereof such as creasing, scoring or offsetting the sheet material so as to weaken its bending resistance without materially weakening the tensile strength. A preferred manner of forming these hinge elements is to offset or deflect the sheet member

slightly or to crush or deform the sheet fibers along the lines of the hinge elements, thus weakening the sheet to bending movement.

The hinge elements or creases 16 are located on the sheet member so as to be positioned substantially at the outer extremities of the article supporting bottom 21 of the completely assembled carrier. The hinge elements 17 are spaced a short distance from the hinge element 16 so as to provide the outer upright article supporting walls 22. The creases or hinge elements 18 are spaced at appropriate distances from the elements 17 so as to form the outer or upper end portions of the structural tension members 23 which are adapted to transmit the load stresses from the container bottom 21 to the upper handle element 26. The hinge elements 19 are utilized principally to provide a swinging connection for the upper article supports 24 which are positioned for engagement with the necks or upper portions of the articles or bottles B, one of which is shown in position in Fig. 2. The hinge element 20 is positioned substantially at the center of length of the sheet member or blank and is in the form of an inverted U-bend located at the upper end of the inner supporting walls 25 of the container. The U-bend 20 thus forms the upper extremity of the complete assembled container, and the upright supporting walls 25 not only form inner sheets extending between the two rows of bottles, but they also serve to transmit the load stresses from the handle 26 formed at the upper portion of the container to the container bottom.

As mentioned, the upper ends of the inner wall sections 25 are formed with a carrying handle 26 suitably constructed to accommodate the hand of the user. The handle 26 may be conveniently formed by providing an opening 27 through one of the companion wall sections 25 and forming a similar opening 28 in the adjacent wall section 25. The handle opening 28 is conveniently formed by providing a cut or slit 29 in the wall section 25. This slit 29 extends laterally slightly beyond the adjacent ends of the opening 27. This construction provides a handle flap 30 having opposite laterally disposed locking lugs or extensions 31. The sheet material at the base of the handle flap 30 is preferably creased or weakened along the lines 32 to provide for deflecting or bending the handle flap from its original position through the handle opening 27 as best shown in Figs. 1 and 3. When the handle flap 20 is thus deflected through the handle opening 27 into its final operative position, the locking lugs 31 will engage the wall member 25 to retain the handle flap 30 in position.

The upper article or bottle neck supports 24 are also provided by making cuts or incisions 33 and 34 through the sheet material of the wall sections 25. These incisions may be appropriately formed to provide seats or serrations 35 for receiving the adjacent necks of the bottles B. It will be noticed that these article supports 24 may be swung outwardly on hinge elements 19 away from the wall sections 25 into positions for convenient engagement therewith of the bottle necks.

At its bottom 21 the carry container is formed also with an additional hinge element 36 along which the bottom may be bent or deflected upwardly. This hinge element 36 extends across the blank or sheet member and is positioned in the assembled container intermediate the width of the bottom 21, or in other words, between the bottom hinge elements 16 of the sheet member. As best shown in Figs. 1 and 4, the bottom hinge element 36 is formed at the connection between

the adjacent bottom sections 37. For this purpose one of the bottom sections 37 is formed with an extension 38 and the other bottom section is formed with complementary spaced extensions

39. Extending from opposite ends of the supporting extension 38 are locking lugs 40 in the form of tabs which may be readily deflected from their original position in the plane of the sheet member. The supporting extensions 39 are also formed with similar locking lugs 41. The supporting extensions 38 and 39 and the locking lugs 40 and 41 are so positioned as to interengage or interlock with each other, thus forming a permanent connection between the ends of the bottom sections 37 as clearly shown in Fig. 4. This permanent connection is made at the factory when the carrier container is manufactured so that the user is not troubled with the assembling of these parts.

When the bottom sections 37 are thus interlocked in assembled relation as described, the locking lugs 40 and 41 engage with each other so as to hold the bottom sections 37 in permanently connected relation. However, these locking lugs may be deflected upwardly at their bases which may be creased or scored at 42 for this purpose when they are interengaged in the manufacturing processes at the factory. Also, it will be clearly seen that the permanent interlocking connection between the bottom sections 37 functions to support the bottom 21 in its normal article supporting position as shown in Figs. 1 and 4. For this purpose the extension 38 contacts with the upper face of the bottom section 37 to provide a bottom support, and the extensions 39 form similar contact with the upper face of the opposite bottom section 37 for a similar purpose. The two bottom sections are fulcrumed or hinged together along the line of the hinge element 36 positioned substantially along the inner base portions of the extensions 38 and 39 and between the adjacent inner edges of the interlocked lugs 40 and 41, and the extensions 38 and 39 thus form supports for limiting the downward movement of the bottom 21 along the hinge element 36. However, these bottom sections 37 may swing upwardly along the hinge element 36 as indicated in Fig. 5. During this deflection or hinging action the lugs 40 and 41 contact with each other adjacent to their base portions to retain the permanent connection at this point, while permitting the upward deflection of the bottom sections 37.

As shown best in Figs. 1 and 7, the blank or sheet member 15 is formed with cuts or slits 43 and 44 adjacent to the carrier tension members 23 so as to form article supports or cushioning members 45. These article cushions or supports 45 form downward extensions of the upper wall sections 25 and are positioned in the set up container in upright position between the two opposed rows of bottles so as to contact with the latter and cushion them against direct engagement with each other, thus preventing breaking or other damage and undue rattling. These article cushions 45 are appropriately proportioned so as to engage at their lower extremities with the container bottom 21 when the container is in set up condition, thus providing a brace or support for holding the carrier in its normal carrying position.

From the foregoing detailed description it will be noticed that the improved carry container includes in its construction a single integral blank or sheet member which is permanently connected into a continuous or endless sheet member. The blank is fabricated and connected in this manner at the factory so that the user has nothing

to do but to execute a simple movement to place the container in a set up or operative condition. The sheet member or blank is integral at the upper part or inverted U-bend 20 of the carry container, and the permanent connection of the blank to form an endless sheet unit is made at the bottom of the container between the bottom sections 37 as described.

After the sheet member or blank 15 has been completely fabricated at the factory, it is assembled by permanently connecting the bottom sections 37 to each other as above described and then collapsed into the position shown in Fig. 6 by deflecting the bottom sections upwardly along the hinge element 36. The blank is thus collapsed into a small space with the plies thereof in face to face contact with each other so that it may be combined with other similar collapsed blanks into a very small space for shipment. When the user desires to set up the container for use, this may be accomplished by a very simple operation requiring no particular skill. In order to accomplish this the bottom sections 37 are swung downwardly along the hinge element 36 as indicated in Fig. 5 into the completely set up position as shown in Fig. 1. The interlocking formations at the adjacent edges of the bottom sections 37 thus cooperate with each other as above described and shown in Figs. 1 and 4 so as to support the bottom in its operative position. The bottles or similar articles may then be placed in the receiving opening between the tension members 23 and the upper parts thereof engaged by the retaining elements 24. The handle flap 30 can be easily inserted into its interlocked position as above described or this operation can be done at the factory.

It will be noticed that the bottom hinge element 36 is equidistant from the upper hinge element 20 in either direction along the opposite container walls. In other words, the distance from the hinge element 36 to the upper hinge element 20 is the same along the right side of the container as it is along the left side. This relationship permits the container to be collapsed into position in which the opposite walls or plies lie in close face to face contact with each other so as to occupy very little space.

It will be noticed that the tension members 23 are connected at their lower ends to outer walls 22, and at their upper ends to the wall sections 25, and that they are inclined upwardly and inwardly toward each other. Due to this arrangement there is a tendency to cause the outer walls 22 and the inner walls 25 to move slightly toward each other when the load stresses incident to supporting the bottles are placed upon the tension members 23. This action results in the bottles being closely engaged by the inner and outer walls so as to retain them in position and to avoid movements thereof in the container and to avoid undue rattling or bumping together of the individual bottles.

Referring to the modified form of the invention as shown in Figs. 8 to 12 inclusive, it will be noted that the general construction and arrangement of the carry container are similar to those of the embodiment described in detail above. For this reason the corresponding parts and elements of this embodiment, those that are similarly arranged and adapted to perform similar functions, are designated by the same reference numerals as in the first embodiment with the addition of the index *a*.

In the embodiment of Figs. 8 to 12, the struc-

ture of the carrier bottom 21a is varied somewhat from that of the first embodiment as indicated in Figs. 8, 9 and 10. In this form, when the container is collapsed, the bottom section 21a is folded along the hinge element 46 positioned at the outer edge portion of the bottom 21a to the left in Fig. 8, instead of being folded along a line intermediate the width of the bottom as in the first embodiment. The bottom sections 31a at the opposite ends of the blank or sheet member are permanently connected together adjacent to the lateral edge portions of the bottom 21a opposite to the collapsing hinge 46.

These adjacent ends of the blank are overlapped with each other as shown in Figs. 8 and 9. The bottom section 31a at the lower extremity of the right outer wall 22a as viewed in Fig. 8 is provided at its terminal with an extension 47 having locking lugs 48 at its opposite extremities, while the adjacent bottom section 31a has an extension 49 normally lying against the inner surface of the wall 22a. Slits or cuts 50 are formed in the bottom section 31a through which the locking or retaining lugs 48 are extended in order to hold the overlapping ends of the blank permanently connected together. Additional permanent attaching means may also be provided for attaching the overlapping end portions of the blank at this point. For example, these overlapping portions of the connecting extension 49 and the wall 22a may be adhesively attached together, or other attaching means such as staples or similar fasteners may be employed. As in the prior embodiment it will be understood that this permanent connection of the overlapping ends of the blank are ordinarily made at the factory when the container is fabricated so that the user is relieved of making this or any other similar connection.

In addition to the hinge elements 16a, 17a, 18a, 19a and 20a corresponding to the similar hinge elements in the prior embodiment of Figs. 1 to 7, this sheet element or blank 15a is provided with an additional hinge element 51 positioned near the upper end of the wall sections 25a and in the vicinity of the handle 26a. This additional hinge element 51 may be formed in a manner similar to that above described in connection with the other hinge elements 16, 17, 18, etc., or it may be scored or otherwise additionally weakened so as to provide for easy folding of the blank along the line of this hinge element.

It will be noticed that the distance along the blank or endless sheet member from the hinge element 46 at the left in Fig. 8 is substantially the same along the bottom and up the right side of the container to the additional or collapsing hinge element 51 as it is up the left side of the container and around the U-band 20a to the same hinge element 51. In other words, the distance between the hinge elements 46 and 51 is the same in either direction from the hinge 46 along the opposite sides of the blank. This relation exists also in the embodiment of Figures 1 to 6, that is, the distance in opposite directions from the hinge 36 along opposite sides of the blank to the hinge 20, is the same at both sides of the carrier. By virtue of this arrangement the container may be collapsed by bending or folding the sheet member along the hinge elements 46 and 51 into substantially the condition shown in Fig. 11 wherein the plies of the endless sheet member lie in close contact relation with each other. This is a condition similar to that described above in connection with Figs. 1 and 7. Also, in the

embodiment of Figs. 8 to 12 the sheet member 15a is permanently connected at the factory into a continuous or endless band which can be collapsed into a small space for shipment as shown in Fig. 11. It can also be very quickly and easily expanded into the set up or operative condition shown in Fig. 8. Since the sheet members are fully fabricated at the factory and all of the permanent connections made there, the carry container can be very quickly and easily set up by the user. This advantage is attained in each of the different embodiments described.

Since certain changes may be made in the above construction and different embodiments of the invention could be made without departing from the scope thereof, it is intended that all matter contained in the above description or shown in the accompanying drawings shall be interpreted as illustrative and not in a limiting sense.

Having described my invention, what I claim as new and desire to secure by Letters Patent is:

In an article carrier, in combination, a structural member including a single sheet permanently connected into an endless structural sheet member, said sheet member having hinge elements extending thereacross at spaced intervals, said sheet member being deflected on certain of said hinge elements to form an article supporting bottom and to form outer upright article retaining walls, said sheet member being deflected on others of said hinge elements to form structural tension members rising above said outer retaining walls and inclining inwardly and upwardly toward each other, and to form also an inner upright 35

supporting wall rising above said inclined tension members, said upright wall including two plies of said sheet member positioned in face-to-face relation and forming a carrying handle at the upper part of the carrier, said carrier having article receiving openings at opposite sides thereof and respectively opening through said inwardly inclined tension members, a supporting member or flap integral with said inner upright supporting wall and extending downwardly from the latter adjacent to said tension members and positioned between the opposing said receiving openings to form an article cushion between the articles, one of said hinge elements being positioned substantially at the upper extremity of said inner supporting wall and forming a collapsing hinge between the plies thereof, a bottom collapsing hinge extending across the carrier substantially at said article supporting bottom intermediate the opposite edges thereof and including overlapping bottom reinforcing parts of said sheet member provided with interlocking formations reinforcing said bottom against downward deflection beyond its normal supporting position and providing for upward hinge movement of the bottom on said bottom hinge, whereby the carrier may be collapsed into a compact substantially flat unit by deflection on said collapsing hinges, said supporting member or flap extending downwardly in contact relation with said article supporting bottom substantially at said upwardly hinging reinforced parts thereof so as to brace the carrier in its normal set up condition.

WM. J. WELLS.
